(57) **CLAIM**

The ornamental design for a pistol as shown and described.

DESCRIPTION

FIG. 1 is a perspective view of the pistol showing our new design;

FIG. 2 is another perspective view thereof;

FIG. 3 is another perspective view thereof;

FIG. 4 is another perspective view thereof;

FIG. 5 is a front view thereof;

FIG. 6 is a back view thereof;

FIG. 7 is a right side view thereof;

FIG. 8 is a left side view thereof;

FIG. 9 is a top view thereof; and,

FIG. 10 is a bottom view thereof.

The broken lines illustrate portions of the pistol and form no part of the claimed design. The bracket in FIGS. 1-4 and 7-10 identify a symbolic break line in broken lines that forms no part of the claimed design.
